C. L. EWING

TRUSS STRUCTURE

Filed March 14, 1928

Inventor
Clement L. Ewing
By Hiram B. Schwartz, Atty.

UNITED STATES PATENT OFFICE.

CLEMENT L. EWING, OF JEROMEVILLE, OHIO.

TRUSS STRUCTURE.

Application filed March 14, 1928. Serial No. 261,645.

My present invention relates to improvements in barn frame truss structures, particularly of the class described in my application filed June 10, 1925, Serial Number 36,270, now pending, and its principal objects are, first to provide a barn frame truss of gothic and semi-gothic type suitable for wider buildings and heavier roofs than usual; secondly, to provide improved means 10 for reinforcing the curved portion of each post and to stiffen and strengthen the entire post of each frame truss, as a unitary structure from bottom to top thereof, and so prevent the sagging of the roof, and also 15 prevent the walls of the building from spreading apart by internal pressure against them. My invention is illustrated by the accompanying drawings in which the figure is a side view of the entire bent made up of 20 a pair of supporting posts which are alike in all respects, only one of which need be identified by reference indicia embodying my invention, the pair of posts being secured together at the apex of the arch by 25 a suitable metal strap X, or other similar means, and at their bottoms by a base-plate Y, or other suitable means, for holding them solidly in position.

The arched post comprises a vertical portion A for the side wall of the building, and 30 a curved portion B for the roof thereof. The two portions are solidly united together as a unitary structure continuous from bottom of the post to the comb of the roof, 35 the curved portion being formed by fastening together a pair of laminated members upon intervening spacer blocks a, a, spaced apart between them in the contour of the arch as in my said former invention. The 40 arched portion is mainly supported by the sloping post C, which is secured by suitable means to the lower end of the post A, and to one of the said spacer blocks a², at its upper end c, by a threaded bolt c' passed 45 thru said spacer block and said pair of laminated members at a point at or near the center of said curved portion of the post B. A short lateral plate E is secured to the post A at or near its junction with the lower 50 end of the curved portion thereof by a threaded bolt b⁴ passed thru the post horizontally and to said sloping post C at or near the middle thereof by a threaded bolt d. If desired, said plate E may be doubled, 55 alike on opposite sides of the posts A and C, for added strength.

At a point at or near the junction of said plates E with the sloping post C is cut a notch c² therein, and a tie-beam D, mounted 60 therein and secured thereto by threaded bolt d' passed thru both members, extends diagonally therefrom to a point under a spacer block a' near the upper end of the curved portion B, and is firmly secured thereto by a threaded bolt d² passed thru said spacer 65 block and laminated members thereon, and the adjacent upper end of said diagonal tie-beam D. A series of struts are interposed between said curved portion and said diagonal tie-beam D, regularly spaced apart 70 and in pairs secured together and to said beam by bolts d³, and at their outer ends, secured in pairs together and to adjacent spacer blocks in the curved portion, by bolts b passed thru said blocks, respectively, said 75 struts being thus secured together endwise in bridge formation. Said struts are further secured at their intersections with the sloping post C by bolts E passed thru both members.

By such construction the curvature of the post is maintained with greater strength and 80 rigidity than has been possible heretofore, and the roof and side portions A, B, of the post are able to prevent both sagging of 85 the roof by the weight thereof and spreading apart of the bent by internal pressure when the truss structure is completed by the junction of the pair of supporting posts, 90 as aforesaid.

If desired, for additional strength of the arch, an intermediate tie-beam F may be 95 interposed between the tie-beam D and the curved portion B of the post, and the upper portion of the sloping post C, as shown in Fig. 1. To this end an additional notch c³ is cut in the sloping post at a point between the notch c and the upper end of the sloping post, and said tie-beam F secured in 100 said notch and to a spaced block a³ midway between spacer blocks a' and a², in the same manner as the tie-beam D is secured, and is further secured at its several intersections with the struts g by bolts j, substantially as shown.

If desired for still greater strength, the 105 several struts may be doubled, and secured together in like manner as hereinbefore stated. When a truss structure is completed on a floor space, it may be raised to position 110 as a bent in the building, and the several bents secured together by longitudinal raft-

ers, the ends of which are shown in section, as at R, against the several adjacent ends of the spacer blocks, and the roof laid on said rafters.

5. What I claim is—

1. A barn frame truss structure comprising in combination, a pair of opposite posts united as a bent, each post having a straight lower portion and a curved upper portion 10 united integrally to form a unitary structure continuous from base to apex thereof, a series of spacer blocks spaced apart between a pair of laminated members in gothic curvature in the curved portion, a sloping post 15 having its lower end solidly attached to the arch post near its lower end, and its upper end solidly attached to the middle of the curved portion opposite a spacer block therein, a horizontal beam solidly attached 20 to said sloping post at or near the middle thereof, and to the arch post at a point opposite thereto, a seat in said sloping post at or near the terminus of said horizontal beam, a tie-beam, its lower end secured in 25 said seat, and its upper end secured to said curved portion opposite a spacer block therein near the upper end of said portion, and a series of diagonal struts spaced apart and 30 spanning the space between said curved portion and said tie beam, said struts arranged and connected endwise in pairs in V-shaped bridge formation, and firmly secured together and to said tie-beam in spaced relation, respectively, and secured together and 35 to adjacent spacer blocks in said curved portion, and to said sloping post where they cross the same, substantially as set forth.
2. A barn frame truss structure, comprising in combination, a pair of opposite posts, 40 each post having a straight lower portion and an upper portion curved inwardly in gothic contour, said portions united to form a unitary structure, a series of spacer blocks spaced apart between a pair of laminated 45 members in said upper portion, a sloping post attached solidly at its lower end to said arch post near its lower end, and at its upper end to the middle of said curved portion, a horizontal beam attached to said 50 sloping post at or near the middle thereof

and to said arch post at a point opposite thereto, a seat in said sloping post opposite the terminus of said horizontal beam, a tie-beam secured in said seat at its lower end, and at its upper end secured to said curved portion near the upper end thereof, a seat in said sloping post intermediate the upper end thereof and the seat for said tie-beam, a secondary tie-beam secured in said intermediate seat, and at its upper end secured to said curved portion at a point mid-way between the upper terminus of said sloping post and of said longer tie-beam, and a series of diagonal struts between said curved portion and said long tie-beam and spaced 60 apart thereon, said struts connected endwise in pairs and secured together in V-shaped bridge formation, and secured to said curved portion and said tie beam, and to said sloping post and intermediate tie-beam at 65 their intersections therewith, respectively, 70 substantially as set forth.

3. A barn frame truss structure having in combination, a pair of opposite arched posts of gothic curvature united together, 75 said posts embodying a unitary structure continuous from the base to the apex of the arch, a sloping post solidly attached at its lower end to said arched post near its lower end, and at its upper end to said arched post at or near the middle of the curved portion thereof, a horizontal beam attached to said sloping post at or near the middle thereof and to said arched post at a point opposite thereto, a tie-beam seated in said 80 sloping post at a point opposite the inner terminus of said horizontal beam, and attached to said arched post near the upper end thereof, and a series of struts extending from the tie-beam to the curved portion of 85 said arched post, said struts arranged in pairs in V-shaped bridge formation, and secured together and to said post and tie-beam respectively, and to said sloping post where they intersect the same, substantially 90 as set forth.

In witness whereof, I hereunto set my hand this 3rd day of December, A. D. 1927.

C. L. EWING.
